(57) **CLAIM**

I claim the ornamental design for a power transfer unit, as shown and described.

DESCRIPTION

FIG. 1 is a top and front side perspective view of a power transfer unit;

FIG. 2 is a right side elevational view thereof;

FIG. 3 is a left side elevational view thereof;

FIG. 4 is a back side elevational view thereof;

FIG. 5 is front side elevational view thereof;

FIG. 6 is a top plan view thereof; and

FIG. 7 is a bottom plan view thereof.

FIG. 8 is a back side perspective view of the power transfer unit, shown in an open position;

FIG. 9 is a left side elevational view thereof;

FIG. 10 is a right side elevational view thereof;

FIG. 11 is a front side elevational view thereof;

FIG. 12 back side elevational view thereof;

FIG. 13 a top perspective view thereof; and,

FIG. 14 is a bottom perspective view thereof.

FIG. 15 is a perspective view of the power transfer unit shown in use and in a partially closed position; and,

FIG. 16 is a perspective view of the power transfer unit shown in use and in an open position.

The broken lines shown represent unclaimed subject matter and form no part of the claimed design.
